WILLIAM C. CARTER, OF ST. LOUIS, MISSOURI, ASSIGNOR TO CARTER CARBURETER COMPANY, OF ST. LOUIS, MISSOURI, A CORPORATION OF MISSOURI.

INTERNAL-COMBUSTION ENGINE.

1,114,107.

Specification of Letters Patent.

Patented Oct. 20, 1914.

Application filed April 25, 1912. Serial No. 893,086.

To all whom it may concern:

Be it known that I, WILLIAM C. CARTER, a citizen of the United States, residing at St. Louis, Missouri, have invented a certain new and useful Improvement in Internal-Combustion Engines, of which the following is a full, clear, and exact description, such as will enable others skilled in the art to which it appertains to make and use the same.

This invention relates to internal combustion engines of the type in which reciprocating valves are arranged inside of the cylinders for controlling the intake and exhaust of the gases to and from the cylinders.

One object of my invention is to provide a four-cycle internal combustion engine of the type referred to which is so designed that the suction and pressure in the cylinders causes the valves to open so as to permit the combustible mixture to enter the cylinders and the burnt gases to escape therefrom, thereby effecting a great saving in the power consumed and consequently producing an engine that will develop more horse-power than one in which the valves are opened by mechanical means.

Another object is to provide a four-cycle internal combustion engine having automatically opening valves that control the inlet and exhaust of the gases, and means propelled by the crank shaft of the engine for governing the position of said valves.

Another object is to provide a four-cycle internal combustion engine whose valve mechanism consists of reciprocating valves that coöperate with ports formed in the sides of the cylinders and imperforate pistons reciprocatingly mounted in the upper end of said cylinders for carrying said valves, and a shaft or shafts provided with cams that control the pistons and thus govern the position of the valves, said cams being preferably inclosed and arranged in such a manner that they can be kept thoroughly lubricated.

Another object is to provide a four-cycle internal combustion engine in which each cylinder has associated therewith a ring-shaped expansion means valve that coöperates with an inlet port and an exhaust port located in different horizontal planes in the side of the cylinder, a carrier for said valve means having a yoke and anti-friction rolls, and a cam shaft provided with cams which are so designed that they will always remain

in engagement with either the yoke or the rollers on said carrier. And still another object is to provide a four-cycle internal combustion engine that embodies the characteristics and features above-mentioned and which is so designed that it can be manufactured cheaply and can be taken apart easily for adjustment or repair.

Figure 1 of the drawings is a vertical sectional view of twin cylinders of an internal combustion engine constructed in accordance with my invention; Fig. 2 is a vertical sectional view of one of the cylinders taken on approximately the line 2—2 of Fig. 1; Fig. 3 is a horizontal sectional view taken on approximately the line 3—3 of Fig. 2; Fig. 4 is a reduced side elevational view of the engine; and Fig. 5 is a rear end elevational view of the engine.

I have herein shown my invention embodied in a four-cycle internal combustion engine having four cylinders which are cast in pairs but I wish it to be understood that it is immaterial, so far as my invention is concerned, whether the cylinders are cast separately, *en bloc*, or in pairs, or whether the engine is provided with one or more cylinders.

Referring to the drawings which illustrate the preferred form of my invention, 1 designates the cylinders of the engine, 2 the main pistons in said cylinders which are operatively connected to the crank shaft 3, and 4 designates the water-jackets of the cylinders. Each cylinder is provided with an inlet port 5 and an exhaust or outlet port 6, said ports preferably consisting of horizontally disposed semi-circular-shaped slots formed in the wall of the cylinder and arranged in different horizontal planes, as shown in broken lines in Fig. 2, the inlet port 5 being located a trifle higher than the exhaust port 6. At approximately the center or middle of the inlet port 5 is a vertically disposed web 5^a whose function will be hereinafter described.

The valve mechanism of each cylinder preferably consists of a reciprocating piston A arranged in the upper end of the cylinder, as shown in Figs. 1 and 2, a valve B carried by said piston for controlling the inlet and exhaust of the gases through the ports 5 and 6, and means for governing or controlling the position of the upper piston A. The piston A is provided with an imperforate

lower end 7 which forms the top wall or upper side of the compression space of the cylinder and with piston rings 8 or some other suitable packing devices that form a tight joint between said piston and the cylinder. In the embodiment of my invention herein shown each of the valves B consists of a split expansion ring which is integrally connected to the piston A that carries same by means 10 of a semi-circular-shaped web b, as shown clearly in Fig. 2; or, stated in another way, the valve B is formed by a depending ring-shaped flange on the lower end of the upper piston A which is separated from the bottom wall 7 of said piston at one point by means of a horizontally disposed semi-circular-shaped slot b', as shown in Fig. 2, and also divided into two halves or sections by means of a diagonal slot or approximately 20 vertically disposed slot b², as shown in Fig. 1, thus forming resilient arms which press tightly against the inner surface of the cylinder. The piston A is arranged in such a manner that the diagonal slot b² in the ring-shaped expansion valve B is located directly opposite the vertical web 5^a at the center of the intake port 5, as shown in Fig. 1. The intermediate portion of the valve B is preferably thicker than the end portions of said 30 valve, as shown in Fig. 3, so as to impart a certain degree of resiliency to the two end portions of the valve that coöperate with the intake port 5, thus causing said end portions to press tightly against the cylinder and 35 consequently holding the intermediate portion of the valve that coöperates with the exhaust port 6 in snug engagement with the inside of the cylinder. I prefer to make the upper piston A substantially hollow, as 40 shown in Figs. 1 and 2, so as to form pockets for a pair of rollers 9 that are loosely mounted on a horizontally disposed shaft 10 that is journaled in bearings in the upper piston A and also in a center bearing 11 on 45 said piston which is arranged between the rollers 9 and thus prevents them from moving longitudinally of the shaft 10, as shown in Fig. 1. The suction and pressure in the cylinder 1 causes the upper piston A to move 50 downwardly and upwardly and thus carry the valve B into and out of operative position with relation to the intake and exhaust ports 5 and 6, respectively, and means is provided for limiting or controlling the 55 movement of said piston so that the valve B will uncover the intake port 5 on the suction stroke, then remain at rest over the ports 5 and 6 on the compression and firing strokes, and thereafter uncover the exhaust 60 port 6 on the scavenging stroke. Said piston-controlling means preferably consists of a cam shaft 12 provided with a pair of cams 13 that coöperate with the rollers 9 on the upper piston A, and an intermediate cam 14 65 that coöperates with a yoke or cross-piece 15

connected to the upper piston A and extending transversely of same, as shown in Figs. 1 and 2, said cams being preferably so designed that they will have a rolling contact on the friction rolls 9 and on the under side 70 of the yoke 15. The yoke or cross-piece 15 is herein shown as being detachably connected to the upper piston A by means of bolts 16, or other suitable fastening devices, and shims 17 are arranged between said piston and cross-piece, as shown in Fig. 2, so as to provide for wear and thus permit the cross-piece 15 to be adjusted accurately with relation to the cam 14 with which it coöperates. 75

If desired, a wear plate 18 can be arranged on the under side of the yoke or cross-piece 15 so as to prevent the cross-piece from becoming worn by the cam 14. In practice, I prefer to use a wear plate that has a slight degree of resiliency and permanently connect said wear plate at one end to the piston or cross-piece, leaving the opposite end of the wear plate free so that it can yield slightly in case the cam 14 becomes worn and thus take up any lost motion between said cam and cross-piece, a stop or pin 19 on the cross-piece coöperating with a bifurcated portion on the wear plate to prevent the free end of the wear plate from shifting or moving with relation to the 95 cam 14.

A spark plug C, or some other suitable ignition device, is arranged in an opening in the side of the cylinder which preferably terminates at its inner end in proximity to the intake port 5 so as to ignite or fire the charge that is drawn into the cylinder on the suction or downward stroke of the main piston 2 of the engine. When the main piston 2 starts to move downwardly on its suction stroke the intake and exhaust ports are both closed by the valve B which has been mechanically moved into this position by the cams 13 that coöperate with the rollers 9 on the upper piston A. On this stroke 100 of the main piston 2 the suction that is produced in the cylinder causes the upper piston A to move downwardly far enough to carry the valve B out of operative position with relation to the intake port 5 but not out of 105 operative position with relation to the exhaust port 6, and thus permit a charge to be drawn into the cylinder through the slot or open space b' between the bottom of the upper piston A and the upper edge of the 110 resilient or expandable portion of the valve B. The upper piston A is thereafter moved upwardly slightly by the intermediate cam 14 just far enough to cause the valve B to 115 cover the intake port 5 and also remain in operative position with relation to the exhaust port 6, the upper piston A being held at rest in this position on the succeeding compression stroke and power or firing 120 stroke of the main piston 2 by means of the 125 intermediate cam 14. The upper piston A is thereafter moved upwardly by the cam 14 just far enough to cause the valve B to uncover the intake port 5 and also remain in operative position with relation to the exhaust port 6, the upper piston A being held at rest in this position on the succeeding compression stroke and power or firing 130 stroke of the main piston 2 by means of the intermediate cam 14.

cams 13 which have dwells or concentric portions that prevent the upper piston A from moving upwardly while the charge is being compressed, fired and expanded, and the intermediate cam 14 having a suitable dwell or concentric portion which merely rolls upon the yoke or cross-piece 15 of the upper piston at these periods in the cycle of operations of the engine. On the fourth stroke or last upward stroke of the main piston 2 the pressure that is created in the cylinder causes the upper piston A to move upwardly and thus carry the expansion valve B out of operative position with relation to the exhaust port 6, thus permitting the burnt gases to escape through said exhaust port into the exhaust manifold 6. The cams 13 and 14 are so designed that they permit the upper piston A to move upwardly on this stroke of the main operating piston 2 just far enough to uncover the exhaust port 6 but not far enough to move the expansion valve B out of operative position with relation to the intake port 5. Consequently, there is no danger of the burnt gases escaping through the intake port 5 on the scavenging stroke of the main operating piston 2 because said intake port 5 is closed at this time by the expansion valve B which is pressed tightly against the inner wall of the cylinder. Before the main piston 2 starts downwardly again on its suction stroke, the upper piston A is moved downwardly far enough by the cams 13 to bring the valve B into operative position with relation to the intake port and exhaust port and thus close said ports so that there will be no danger of the burnt gases being sucked back into the cylinder.

From the foregoing it will be seen that the valve B is moved automatically by the suction and pressure created in the cylinder to open the ports, and that it is actuated mechanically when it is moved to close the intake port and exhaust port. Consequently less power is consumed in operating the valves of such an engine than an internal combustion engine in which the valves are opened by mechanical means or by some moving part of the engine that exerts pressure on the valve-operating mechanism. In other words, my engine is so designed that the valves are opened automatically by the suction in the cylinders to draw the charges of combustible gas into the cylinders, and are opened automatically by the pressure created in the cylinders to permit the burnt gases to escape therefrom, the only mechanical actuation of the valves being the closing of the valves and this being effected by cams that have a rolling contact with the upper piston A, and which are so designed that they hold said upper piston at rest while the charge is being compressed and fired, thereafter permit said piston to be

moved upwardly by the pressure exerted against the imperforate bottom wall thereof so as to permit the burnt gases to escape, and finally permit the piston to be moved downwardly by the suction created on the 70 suction stroke of the main piston so as to permit the gas to be drawn into the cylinders.

In view of the fact that the expansion valve B is located close to the upper limit of travel of the main piston 2, the oil which the piston 2 throws upwardly onto the walls of the cylinder will thoroughly lubricate the valve B and the surface of the cylinder on which said valve slides. In other words, the 80 upward stroke of the main piston 2 causes oil to be thrown upwardly onto the side walls of the cylinder about one-half to five-eighths of an inch above the piston 2 when it is at the upper end of its stroke and consequently a thin film of oil will always be provided on the side walls of the cylinder for the valve to slide in. If desired, oil grooves 33 can be formed in the walls of the cylinder in proximity to the intake and 85 exhaust ports so as to retain some of the oil and thus distribute it over the outer surface of the expansion valve B which slides back and forth over the inner surface of the cylinder. Some suitable means, not shown, is 90 employed for supplying oil to the hollow upper piston A so as to lubricate the rollers and cams forming part of the mechanism that controls or governs the position of said upper piston, Fig. 2 showing the upper piston A as being partially filled with oil so that the rotary movement of the rollers 9 and the reciprocating movement of the piston A will cause the oil to be splashed 95 up over the cams 13 and 14 and thus lubricate said cams, rollers, and the yoke 15. In the engine herein shown a separate cam shaft 12 is provided for each pair of cylinders, and bearings 20 for said shaft are set in notches or recesses in the upper ends of the cylinders 1, the cylinders being so proportioned that the upper sides of said bearings 20 will extend flush with the upper edges of the cylinders. The bearings 20 preferably project laterally into the path of 110 movement of the upper piston A, and slots are formed in said piston to receive said bearings, as shown particularly in Fig. 2, the bearings 20 thus acting to guide the upper piston and prevent it from rotating. Caps or covers 21 rest upon the upper edges of the cylinders and are secured in position by bolts or other suitable fastening devices so as to completely incase the cams and 115 rollers of the valve mechanism and also clamp the bearings 20 of the cam shafts in position. Where separate cam shafts are provided for each pair of cylinders, as herein shown, said shafts will, of course, be connected together by some suitable means so 120 125 130

that they will rotate in unison, and a chain or gears are provided for transmitting rotary movement from the crank shaft 3 to the cam shafts 12, the means herein shown for driving the cam shafts consisting of a spiral gear 22 on the crank shaft that meshes with a spiral gear 23 on the lower end of a vertically disposed shaft 24 which is provided at its upper end with a spiral gear 25 that meshes with a spiral gear 26 on the cam shaft 12, as shown in broken lines in Figs. 4 and 5 and partly in full lines in Fig. 1. A housing 27 of any suitable type is provided for incasing the shaft 24 and the spiral gears just described. If desired, the vertically disposed shaft 24 may be provided with a gear 28 that meshes with a gear 29 on a horizontal shaft 30 which drives the magneto M and the pump P that forces water through the water-jackets of the cylinders. If desired, this vertically disposed shaft 27 may be extended downwardly, as shown in broken lines in Figs. 4 and 5, so as to operate a pump, not shown, which forces the oil in the bottom of the crank case W to any part of the engine which it is desired to lubricate. In order to prevent excessive pressure from being created on the upper side of the top piston A or between said piston and the cap 21 which is mounted on the upper end of the cylinder, I have provided each cylinder with a suction passageway or conduit 31 that establishes communication between the space above the piston A and a suction-producing device which may be a pump or the gas manifold 5^b that communicates with the cylinder. By eliminating pressure on the upper side of the piston A in this manner I prevent the oil in said upper piston from being forced out through the bearings of the cam shaft 12 or between the outer surface of said piston A and the inner surface of the cylinder and consequently I am able to maintain an oil level in the piston A. And still another advantage of the conduit or passageway 31 is that it creates a partial vacuum on the upper side of the piston A or exerts a slight suction on the upper side of the piston A when the main piston 2 moves downwardly on its suction stroke and thus reduces the pressure on the cross-piece 15 with which the cam 14 co-operates. In other words, the suction that is created on the upper side of the piston tends to retard the downward movement of said piston and thus prevents excessive strains from being placed upon the cross-piece or yoke 15 of the top piston A, it being, of course, understood that the suction that is created above the piston is so much less than the suction created on the under side of the piston that it does not prevent the piston from moving downwardly on the suction stroke of the main piston 2 so as to automatically open the inlet port 5. Preferably, a check valve 32 is arranged in

the passageway 31 so as to eliminate the possibility of gas being sucked up through said passageway into the space above the top piston A.

While I have herein stated that the expansion valves B which control the flow of the gases into and out of the cylinders are preferably cast integral with the upper pistons A, I do not wish it to be understood that my broad idea is limited to such a construction for the same results could be accomplished with split spring expansion rings or numerous other kinds of expansion valves of substantially ring-shape arranged in such a manner that they will reciprocate up and down with the pistons A in the upper ends of the cylinders.

An engine of the construction above-described can be manufactured at a low cost because the bore or internal diameter of the cylinder 1 is uniform or constant throughout its entire length; because the cams 13 and 14 which form part of the valve mechanism are external cams, as distinguished from internal cams or cams consisting of blocks of metal in which irregular grooves are formed; and because it is not necessary to fit the valves B accurately to the cylinders so as to provide for expansion and contraction of the metal, this, of course, being due to the fact that the valves B are expandible. Furthermore, such an engine can be taken down quickly and easily for adjustment or repair, and as means is provided for taking up lost motion or wear between the top piston A and its controlling mechanism, the valves can be adjusted accurately with relation to their co-operating ports.

Having thus described my invention, what I claim as new and desire to secure by Letters Patent is:

1. A four-cycle internal combustion engine provided with valves and a valve-actuating member that is operated by the suction and pressure in the cylinders to automatically open the intake ports and exhaust ports, respectively, and means that positively moves said valve-actuating member to close said ports.

2. A four-cycle internal combustion engine provided with valves and a valve-operating member that is moved automatically by the suction and pressure in the cylinders to open the intake ports and exhaust ports, respectively, and means that positively moves said member so as to cause the valves to close said ports, said means also operating to hold the valves at rest and in position to close both the intake and exhaust ports on the compression and power strokes of the pistons.

3. A four-cycle internal combustion engine comprising a cylinder provided with an intake port and with an exhaust port, an expansion valve arranged in said cyl-

inder for controlling the inlet and exhaust of the gases to and from said cylinder, means whereby the suction and pressure created in the cylinder on the suction and scavenging strokes, respectively, of the piston causes said valve to move automatically to open said ports, and means for moving said valve to close said ports at the proper periods in the cycle of operations of the engine.

10 4. A four-cycle internal combustion engine comprising a cylinder provided with an intake port and with an exhaust port, an expansion valve arranged in said cylinder for controlling the inlet and exhaust of the 15 gases to and from said cylinder, means whereby the suction and pressure created in the cylinder on the suction and scavenging strokes, respectively, of the piston causes said valve to move automatically to open 20 said ports, and means which limits the opening movement of said valve and also holds the valve in coöperative position with both ports on the compression and power strokes of the piston.

25 5. A four-cycle internal combustion engine comprising a cylinder provided with intake and exhaust ports, a ring-shaped expansion valve reciprocatingly mounted inside of the cylinder for controlling the inlet and exhaust of the gases to and from the cylinder, means whereby the suction and pressure created in the cylinder on the suction and scavenging strokes, respectively, of the piston causes said valve to move automatically to open said ports, and means for 30 positively moving said valve to close said ports after the burnt charge has been expelled from the cylinder.

40 6. A four-cycle internal combustion engine comprising a cylinder provided with intake and exhaust ports, a ring-shaped expansion valve reciprocatingly mounted inside of the cylinder for controlling the inlet and exhaust of the gases to and from the cylinder, means whereby the suction and pressure created in the cylinder on the suction and scavenging strokes, respectively, of the piston causes said valve to move automatically to open said ports, and means 45 which limits the movement of said valve and holds the valve in position to close both ports while the charge is being compressed, fired and expanded.

55 7. A four-cycle internal combustion engine comprising a cylinder provided with intake and exhaust ports, a main piston in said cylinder, a separate piston reciprocatingly mounted in the upper portion of the cylinder and provided with an imperforate wall that forms the top of the compression space of the cylinder, means carried by said upper piston that coöperates with said ports for controlling the inlet and exhaust of the gases to and from the cylinder, and means 60 for permitting said upper piston to move

downwardly far enough on the suction stroke of the main piston to permit a charge to enter the cylinder through the intake port and for permitting said upper piston to move upwardly far enough on the scavenging stroke of the main piston to permit the burnt gases to escape from the cylinder.

70 8. A four-cycle internal combustion engine comprising a cylinder provided with intake and exhaust ports, a main piston in said cylinder, a separate piston reciprocatingly mounted in the upper portion of the cylinder and provided with an imperforate wall that forms the top of the compression space of the cylinder, means carried by said upper piston that coöperates with said ports for controlling the inlet and exhaust of the gases to and from the cylinder, means for permitting said upper piston to move downwardly far enough on the suction stroke of the main piston to permit a charge to enter the cylinder through the intake port and for permitting said upper piston to move upwardly far enough on the scavenging stroke of the main piston to permit the burnt gases to escape from the cylinder, and means for limiting the movement of said upper piston when it is sucked downwardly on the suction stroke of the main piston and moved upwardly on the scavenging stroke of said main piston and also for holding said upper piston in such a position on the compression and power strokes of the main piston that both the intake and exhaust ports are closed.

85 9. A four-cycle internal combustion engine comprising a stationary cylinder provided with intake and exhaust ports, a main piston arranged in said cylinder, a separate piston reciprocatingly mounted in the upper portion of the cylinder and having an imperforate bottom that forms the top wall of the compression space of the cylinder, a valve means carried by said upper piston for controlling the inlet and exhaust of the gases through both of said ports, and a controlling means for said upper piston which holds said valve means in position to close both the intake and exhaust ports on the compression and power strokes of the piston, said controlling means also acting to positively move said piston so as to close the ports after the piston has been moved automatically by the suction and pressure created in the cylinder on the suction and scavenging strokes of the main piston, respectively.

100 120 10. A four-cycle internal combustion engine comprising a cylinder having intake and exhaust ports formed in the walls thereof, a main piston arranged in said cylinder, an expansion valve arranged in said cylinder 105 and coöperating with said ports for controlling the inlet and exhaust of the gases to and from the cylinder, a reciprocating carrier for said valve arranged in the upper portion 110 of the cylinder and having an imperforate 115

125 130

portion that forms the top wall of the compression space, and a controlling and actuating mechanism for said valve carrier arranged above same for moving said carrier positively in opposite directions, said mechanism also holding the carrier at rest on the compression and power strokes of the main piston.

11. An internal combustion engine having 10 inlet and exhaust ports formed in the walls of the cylinder at opposite sides of same through which the gases enter and escape from the cylinder, a valve reciprocatingly mounted inside of said cylinder and coöperating with both of said ports for controlling the inlet and exhaust of the gases, and a controlling and actuating mechanism for said valve arranged above same and comprising a cam for positively moving the valve in one 20 direction, a separate cam for positively moving the valve in the opposite direction, and a horizontally disposed shaft that moves said cams and which prevents the valve from rotating in the cylinder.

12. An internal combustion engine having inlet and exhaust ports formed in the walls of the cylinder at opposite sides of same through which the gases enter and escape from the cylinder, a valve reciprocatingly mounted inside of said cylinder and coöperating with both of said ports for controlling the inlet and exhaust of the gases, a piston carrier for said valve reciprocatingly mounted in the upper portion of the cylinder which 30 is the same bore as the lower portion of the cylinder, piston rings on said carrier, said carrier having an imperforate portion that forms the top wall of the compression space, and a controlling and actuating mechanism 35 for said carrier arranged above same and comprising cams that move said carrier positively in opposite directions so as to cut off the inlet and exhaust of the gases.

13. An internal combustion engine having 45 inlet and exhaust ports formed in the walls of the cylinder through which the gases enter and escape from the cylinder, a valve reciprocatingly mounted inside of said cylinder and coöperating with both of said ports 50 for controlling the inlet and exhaust of the gases, a carrier for said valve reciprocatingly mounted in the upper portion of the cylinder, a yoke on said carrier, and a cam shaft 55 extending transversely across the upper end of the cylinder through slots in the valve-carrier and provided with cams that are arranged between said carrier and yoke for controlling the position of the carrier.

14. A four-cycle internal combustion engine 60 comprising a cylinder having intake and exhaust ports formed in the walls thereof, a reciprocating carrier arranged in the upper portion of said cylinder and provided with means that cooperates with said ports 65 for controlling the inlet and exhaust of the

gases to and from the cylinder, a shaft extending transversely across the upper end of the cylinder and provided with cams that govern the movement of said carrier and hold it in such a position on the compression 70 and power strokes that both ports are closed, said carrier having vertically disposed openings through which said cam shaft passes, whereby said carrier is prevented from rotating, and means for enabling said carrier 75 to be adjusted with relation to said cams.

15. A four-cycle internal combustion engine comprising a cylinder having inlet and exhaust ports formed in the walls thereof, a valve means arranged inside of said cylinder 80 for controlling the flow of the gases through said ports, a reciprocating carrier for said valve means arranged in the upper portion of said cylinder and provided with a yoke or cross-piece, and a horizontal shaft passing through said yoke and provided with cams that coöperate with the yoke and with the carrier for moving the carrier and governing the position of same, said carrier being so constructed that said shaft passes through 85 same and thus prevents the carrier from rotating.

16. In a four-cycle internal combustion engine, a reciprocating valve carrier arranged in the upper portion of the cylinder 95 of the engine and provided with a yoke or cross-piece, a horizontal shaft passing through said yoke and provided with cams that coöperate with the yoke and with the carrier for moving the carrier and governing the position of same, means for enabling 100 said yoke to be adjusted with relation to said carrier, and anti-friction rollers on said carrier that coöperate with some of said cams.

17. In a four-cycle internal combustion engine, a reciprocating valve carrier arranged in the upper portion of the cylinder of the engine and provided with a yoke or cross-piece, a horizontal shaft passing 110 through said yoke and provided with cams that coöperate with the yoke and with the carrier for moving the carrier and governing the position of same, and a wear plate on the under side of said yoke that coöperates with one of said cams, one end of said wear plate being fixed or secured and the opposite end being free so that it can move slightly and thus automatically take up the wear on said cam or yoke.

18. A four-cycle internal combustion engine comprising a cylinder having intake and exhaust ports formed in the walls thereof, a reciprocating piston arranged in the upper end of said cylinder so as to form the top wall of the compression space and provided with an expansible valve means that coöperates with said ports to control the inlet and exhaust of the gases to and from the cylinder, and means whereby said 120

- valve means moves to open said inlet and exhaust ports on the suction and scavenging strokes of the piston and to close said ports on the compression and power strokes of the piston, said valve means and ports being so arranged that the gases pass over the upper edge of the valve when entering the cylinder and pass under the lower edge of the valve when escaping from the cylinder.
19. A four-cycle internal combustion engine having inlet and exhaust ports formed in the walls thereof, a reciprocating piston arranged in the upper end of said cylinder, and a split-ring expansion valve carried by said piston and coöperating with both of said ports for controlling the inlet and exhaust of the gases, said valve being integrally connected to said piston at one point by means of a web.
20. An internal combustion engine comprising a cylinder that has inlet and exhaust ports formed in the walls thereof, and a reciprocating piston arranged in the upper end of said cylinder and provided with an integral depending ring-shaped flange that coöperates with said ports to control the inlet and exhaust of the gases, said flange being divided into two sections and separated from said piston at one point by means of a semi-circular-shaped slot.
21. A four-cycle internal combustion engine comprising a stationary cylinder having inlet and exhaust ports, a reciprocating piston arranged in the upper portion of said cylinder and provided with means that coöperates with both of said ports to control the inlet and exhaust of the gases, a chamber or pocket on the upper side of said piston for holding a lubricating medium, and cams arranged in said chamber above said piston that actuate and control the piston.
22. An internal combustion engine having an open-ended cylinder which is provided in its walls with inlet and exhaust ports, a main piston arranged in the lower portion of said cylinder, a separate piston arranged in the upper portion of said cylinder and provided with means that coöperates with said inlet and exhaust ports for controlling the inlet and exhaust of the gases, a cap or cover arranged over the upper end of said cylinder, a controlling and actuating mechanism for said upper piston arranged above same, and means for preventing excessive pressure from being created in the space between the upper side of said upper piston and said cap.
23. An internal combustion engine having an open-ended cylinder which is provided in its walls with inlet and exhaust ports, a main piston arranged in the lower portion of said cylinder, a separate piston arranged in the upper portion of said cylinder and provided with means that coöperates with said inlet and exhaust ports for controlling the inlet and exhaust of the gases, a cap or cover arranged over the upper end of said cylinder, a controlling and actuating mechanism for said upper piston arranged above same, and means for exerting suction on the upper side of said upper piston so as to retard the downward movement of same on the suction stroke of the main piston in the lower portion of the cylinder.
24. An internal combustion engine having an open-ended cylinder which is provided in its walls with inlet and exhaust ports, a main piston arranged in the lower portion of said cylinder, a separate piston arranged in the upper portion of said cylinder and provided with means that coöperates with said inlet and exhaust ports for controlling the inlet and exhaust of the gases, a cap or cover arranged over the upper end of said cylinder, a controlling and actuating mechanism for said upper piston arranged above same, and a conduit or passageway that establishes communication between a suction-producing means and the space between said upper piston and cap.
25. An internal combustion engine having an open-ended cylinder which is provided in its walls with inlet and exhaust ports, a main piston arranged in the lower portion of said cylinder, a separate piston arranged in the upper portion of said cylinder and provided with means that coöperates with said inlet and exhaust ports for controlling the inlet and exhaust of the gases, a cap or cover arranged over the upper end of said cylinder, a controlling and actuating mechanism for said upper piston arranged above same, a suction passageway leading from the gas inlet manifold to the space between said upper piston and cap, and a check-valve in said suction passageway.
26. A four-cycle internal combustion engine comprising a cylinder having oppositely disposed semi-circular-shaped slots formed in the walls thereof and located in different horizontal planes to form inlet and exhaust ports, a ring-shaped expansion valve reciprocatingly mounted in said cylinder and coöperating with both of said ports to control the inlet and exhaust of the gases, and means whereby said valve is moved downwardly automatically by the suction in the cylinder on the suction stroke so as to uncover the inlet port, thereafter upwardly by a positively acting means so as to cover both of said ports on the compression and power strokes and upwardly still further by the pressure in the cylinder on the scavenging stroke to permit the burnt gases to escape from the exhaust port.
27. A four-cycle internal combustion engine comprising a cylinder having inlet and

exhaust ports formed in the walls thereof, a main piston arranged in said cylinder, a separate piston arranged in the upper portion of the cylinder, an expansible valve 5 means on said upper piston that coöperates with both of said ports to control the inlet and exhaust of the gases, a pocket or chamber in said upper piston for holding a lubricating medium, a cam shaft arranged above 10 said upper piston and provided with cams that actuate and control the movement of said upper piston, a cap or cover that incloses said upper piston and cams, and a suction pipe that communicates with the space 15 above said upper piston.

28. A four-cycle internal combustion engine comprising a cylinder having inlet and exhaust ports formed in the walls thereof, a head or closure for the upper end of said 20 cylinder, a main piston arranged in the lower part of the cylinder, a separate piston arranged in the upper portion of the cylinder, means carried by said upper piston and coöperating with said ports for controlling 25 the flow of the gases into and out of the cylinder, means arranged in the space above said upper piston for controlling the movement of said piston, and a suction passage-way that communicates with the space above 30 said upper piston.

29. An internal combustion engine comprising a cylinder having intake and exhaust ports formed in the side walls thereof, a main piston in said cylinder, and a reciprocating valve coöperating with said ports and arranged inside of said cylinder in such a manner that it partially overlaps the stroke 35 of the piston, thereby causing the surfaces of the cylinder on which said valve slides to 40 be lubricated by the upward stroke of the piston.

30. An internal combustion engine comprising a cylinder having intake and exhaust ports formed in the side walls thereof, a reciprocating expansion valve inside of said 45 cylinder that coöperates with said ports, and oil grooves formed in the inner surface of said cylinder for lubricating said valve.

31. In an internal combustion engine, the combination with the cylinder, piston and freely expansible controlling valve pressed 50 to its seat by the internal pressure in the

cylinder, of compensating devices subject to the internal pressure in the cylinder and connected to the controlling valve to move the 55 same against the resistance created by the internal pressure.

32. In an internal combustion engine, the combination with the cylinder, piston, freely expansible controlling valve pressed to its 60 seat by the internal pressure in the cylinder and actuating devices therefor, of compensating devices subject to the internal pressure in the cylinder and connected to the controlling valve to assist in the movement 65 thereof against the resistance created by the internal pressure.

33. In an internal combustion engine, the combination with the cylinder, piston and freely expansible controlling valve pressed 70 to its seat by the internal pressure in the cylinder, of a secondary piston subject to the internal pressure in the cylinder and connected to the controlling valve to move the same against the resistance created by the 75 internal pressure.

34. In an internal combustion engine, the combination with the cylinder, piston and expansible sleeve-like valve subject internally to the internal pressure in the cylinder 80 and pressed to its seat thereby, of compensating devices also subject to the internal pressure in the cylinder and connected to the valve to move the same against the resistance created by the internal pressure. 85

35. In an internal combustion engine, the combination with the cylinder, piston and expansible sleeve-like controlling valve subject internally to the internal pressure in the cylinder and pressed to its seat thereby, and 90 actuating means therefor, of compensating devices also subject to the internal pressure in the cylinder and connected to the valve to assist the actuating devices in the movement thereof against the resistance created by the 95 internal pressure.

In testimony whereof I hereunto affix my signature in the presence of two witnesses, this fifteenth day of April, 1912.

WILLIAM C. CARTER.
